CLAIM

The ornamental design for a hand-held filmstrip viewer, as shown and described.

DESCRIPTION

FIG. 1 is a side elevational view of a hand-held filmstrip viewer showing my new design;
FIG. 2 is a front elevational view thereof;
FIG. 3 is a top plan view of FIG. 1;
FIG. 4 is a bottom plan view of FIG. 1;
FIG. 5 is a side elevational view thereof, opposite of that shown in FIG. 1; and,
FIG. 6 is a rear elevational view thereof.
